ATTORNEY

UNITED STATES PATENT OFFICE

113,875

DESIGN FOR A PERFUME BOTTLE

Shozo Miyaki, Honolulu, Territory of Hawaii

Application November 23, 1938, Serial No. 81,324

Term of patent 7 years

To all whom it may concern:

Be it known that I, Shozo Miyaki, a citizen of United States of America, residing at Honolulu, in the county of Honolulu and Territory of Hawaii, have invented a new, original, and ornamental Design for Perfume Bottles, of which the following is a specification, reference being had to the accompanying drawing, forming a part thereof, in which,

I claim:

The ornamental design for a perfume bottle, as shown.

SHOZO MIYAKI.
